UNITED STATES PATENT OFFICE

RICHARD S. COWAN, OF FORT WORTH, TEXAS, ASSIGNOR, BY MESNE ASSIGNMENTS, TO
GENERAL ICE SCORING MACHINE COMPANY, A CORPORATION OF DELAWARE

ICE-SCORING MACHINE

Application filed December 13, 1928. Serial No. 325,729.

This invention relates to machines for making scores in the sides of ice cakes or blocks in order to expedite the breaking of the cakes or blocks into smaller pieces.

- 5 An object of the invention is to provide a machine having scoring devices for forming transverse and longitudinal scores on cakes or blocks of ice and for automatically controlling the operation of the machine so that
10 the transverse scores will be properly formed. Another and a specific object of the invention is to provide a machine having devices for forming horizontal scores along the sides of cakes or blocks of ice automatically and as
15 an incident to the movement of the cakes or blocks horizontally through the machine, in combination with an elevator mechanism for raising and lowering the cakes or blocks of ice vertically in the machine, and means for
20 automatically forming vertical scores in the sides of the cakes or blocks of ice during operation of the elevator.

Other objects will appear from the following description, reference being made to the
25 drawings in which

Fig. 1 is a side elevation of my improved machine.

Fig. 2 is a front end elevation.

Fig. 3 is a vertical cross sectional view approximately on the line 3-3 of Fig. 1.

Fig. 4 is a sectional view of a clutch device included in the machine controlling the operation of parts of the mechanism.

Fig. 5 is a top plan view of parts of the
35 mechanism, some of the parts of the frame etc. being shown in section.

Fig. 6 is an enlarged detail sectional view of parts of the driving mechanism.

Fig. 7 is a plan view of the train of gearing
40 for operating the devices for forming horizontal scores in the sides of the cakes or blocks of ice.

My improved machine comprises two vertical side frames, each including upright
45 frame members 1, 2 and 3; a lower horizontal frame member 4 attached to the lower ends of the upright frame members 1, 2 and 3 along each side; an upper horizontal frame member 5 attached to the upper ends of the
50 frame members 1, 2 and 3 along each side;

a horizontal frame member 6 attached to the upright frame members 1 and 2 at each side; a cross connection 7 rigidly connecting the lower horizontal frame members 4; end cross connections 8 and 9 rigidly connecting the upper ends of the upright frame members 1 and 3, respectively; and an intermediate cross connection 10 rigidly connecting the upper ends of the upright frame members 2.

An elevator frame for receiving and raising the cakes or blocks of ice is mounted in the front end of the machine. The elevator comprises a pair of frame members, each including a vertical side portion 11 mounted adjacent to the frame members 2 and 3, respectively, and having a laterally extended lower arm 12 and a laterally extended upper arm 13. The lower arms 12 are connected by a base member 14 and the upper arms 13 are connected by a bar 15. Each of these elevator frames has rigid therewith a notched bracket 16 (Fig. 1), in the notches of which the flanges of the upright frame members 2 and 3 are received. Thus, the elevator is properly guided in its ascent and descent because the brackets 16 prevent lateral oscillation of the elevator in either direction. A pair of chains 17 have their lower ends attached to the bar 15 of the elevator, which is approximately midway between the lateral sides of the elevator, and their upper ends attached to spirally grooved rolls 18 rigid on a shaft 19. This shaft 19 has one end journaled for rotation in the frame member 9 and the opposite end attached to a clutch member 20 which is journaled for rotation in the frame member 10. Obviously, rotation of the shaft 19 in one direction will raise the elevator and rotation of said shaft in the opposite direction will permit the elevator to descend.

A pair of vertical shafts 21 have their lower ends journaled in bearings 22 on the respective lower frame members 4 and their upper ends journaled in bearings 23 on the respective frame members 6. A circular peripherally grooved cutter or saw 24 is attached to each of the shafts 21. These cutters are in such positions that they will form horizontal grooves in the opposite sides of an ice cake

or block moving between them. The upper ends of each of the shafts 21 has a beveled pinion 25 rigid thereon meshing with pinions 26 respectively on the ends of a shaft 27 appropriately supported and journaled for this relationship of the parts.

A horizontal shaft 28 is journaled for rotation in the frame members 2 and 3 at one side of the machine and a similar shaft 29 is journaled for rotation in the frame members 2 and 3 at the opposite side of the machine. A motor 30 is mounted upon the frame members 6 and drives a sprocket 31 connected by a chain 32 with a sprocket 33 on the shaft 28 and thereby rotates said shaft 28 continuously in one direction when the motor is running. The shaft 28 has a pinion 34 meshing with the pinion 25 and thereby, through the gearing above described, rotates both shafts 21; and by a pinion 35 on the shaft 29 also rotates said shaft 29. Each of the shafts 28 and 29 has a number of circular peripherally toothed cutters or saws 36 attached thereto so that automatically and as an incident to the raising and lowering of the elevator the cake or block of ice on the elevator and moved between the cutters or saws 36 will be formed with vertical grooves on its opposite sides transversely of the grooves formed by the cutters or saws 24.

A belt drum 37 is attached to the shaft 29 and is engaged by two belts 38 and 39. The belt 39 is shiftable to and from engagement with an idler pulley 40 mounted on a cylindrical shaft 41 and to and from engagement with a pulley 42 attached to said shaft 41. The belt 38 is shiftable to and from engagement with an idler pulley 43 loose on the shaft 41 and to and from engagement with a pulley 44 attached to said shaft 41. The belt 39 is twisted and will rotate the pulley 42 and thereby the shaft 41 in a direction opposite from that in which the belt 38 will rotate the pulley 44 and thereby said shaft 41. The tubular shaft 41 is mounted on antifriction bearings 45 supported on a shaft 46. One end of the shaft 46 is journaled for rotation in an antifriction bearing 47 (Fig. 6) in the end frame member 8 and the opposite end of said shaft 46 is journaled in an antifriction bearing 48 in the clutch member 20, which is attached to and supports the shaft 19, as described. A clutch member 49 is loose on the shaft 46 adjacent to the end of the shaft 41. An intermediate clutch member 50 is splined for sliding movements along the shaft 46 and is shiftable from clutching engagement with the clutch member 20 to clutching engagement with the clutch member 49, or to position out of engagement with both of said clutch members, as desired. The clutch member 50 is engaged by a fork 51 attached to the inner end of a rod 52 which is mounted for longitudinal sliding movements in the upper frame members 9 and 10. A spring 53

(Fig. 1) which encircles the rod 52 has one end abutting against the frame member 9 and the opposite end against a collar 54 on said rod 52 and functions to impel and, under certain conditions, to actuate said rod 52 in a direction to disengage the clutch member 50 from the clutch member 20 and to engage said clutch member 50 with the clutch member 49.

The tubular shaft 41 has a pinion 55 (Figs. 5 and 6) attached thereto and meshing with a gear 56 attached to a shaft 57 and journaled for rotation in the upper frame members 8 and 10. A pinion 58 on the shaft 57 is thus driven by the gear 56 and is in mesh with a gear 59 attached to the shaft 46. Thus, I have provided a speed reduction gearing for driving the shaft 56 in either direction by the driving connections including the pulleys 42 and 44 which may be driven optionally to rotate the shaft 41 in either direction. The arrangement is such that when the belt 38 engages the pulley 44 the belt 39 engages the idler pulley 40; and when the belt 38 engages the idler pulley 43 the belt 39 essentially engages the pulley 42 so that one of said belts is always in effective position.

The clutch member 49 is provided with a sprocket wheel 60 which is connected by a chain 61 with a sprocket wheel 62 attached to a rotary shaft 63. The shaft 63 by beveled gearing 64 drives a vertical rotary shaft 65. The lower end of the rotary shaft 65 supports a sprocket wheel 66 and a similar sprocket wheel 67 is supported in front of one of the vertical frame members 3. An endless sprocket chain 68 is mounted on the sprocket wheels 66 and 67 and has a pair of laterally projecting arms 69 thereon which operate to engage the rear of the ice cakes or blocks and move them from the machine after they have been vertically scored by the scorers 36.

A rod 70 is journaled for rocking movements in bearings 71 attached to the upright frame member 3 which is enclosed between the sides of the chain 68. The lower end of the rod 70 is an angular arm 72 which is arranged to be engaged by lugs 73 projecting upwardly from the arms 69. Thus, the rod 70 is turned in a direction and to an extent to shift the belt 38 from the active pulley 44 to the idler pulley 43 and to shift the belt 39 from the idler pulley 40 to the active pulley 42. The belt shifter comprises a rod 74 having its forward end pivoted to an arm 75 attached to the upper end of the rod 70 and having its rear end connected with a rod 76 by a union 77 (Fig. 1), the opposite end of which rod 76 is mounted for sliding movements in the frame member 8. Brackets 78 on the rod 76 engage the belts 38 and 39 to shift said belts as described. Thus, it will be seen that the rod 70 has two positions. That is to say, said rod 70 has one position in which the belts 38 and 39 are engaged with the pulleys 44 and 40, respectively, and has

another position in which said belts are engaged with the pulleys 43 and 42, respectively. The rod 70 and its connected parts are retained in its two positions by a snap action device such as a counterweight device 79 mounted on a pivot 80 (Fig. 1) and having an arcuate rack 81 meshing with a rack 82 attached to the rod 74.

A slide 83 is mounted for vertical sliding movements between the frame members 2 and in its lower position constitutes an abutment to stop a cake or block of ice in proper position on the elevator when the cake or block of ice is moved into the machine (Figs. 1 and 5). The end of the base member 14 projects under the slide 83 in the lower position of said slide and functions to raise the slide when the elevator rises. An angular arm 84 is attached to the upper end of a rod 85 supported for rocking movements by a frame member 2. In the lower position of the slide 83 the free end of the arm 84 abuts against the side edge of the slide 83 and hence does not interfere with the upward movement of the slide. 25 When the slide 83 is raised by the elevator base 14 said slide is moved to a position above the arm 84. Said arm 84 is thereupon moved under the lower edge of the slide 83 by means of a spring 86 connected to an arm 87 attached 30 to the lower end of the rod 85 and acting to turn the rod 84 in a direction to cause the arm 84 to project under the slide 83 (Fig. 5). The arm 87 projects over the chain 68 and at the proper time is engaged by one of the lugs 73 35 and thereby moved to turn the rod 85 in a direction and to an extent to disengage the arm 84 from under the slide 83 and permit said slide to drop to its lower position.

In operation a cake or block of ice is pushed onto the elevator base 14 until stopped by the abutment slide 83. When the cake or block of ice is properly positioned in the machine the rod 52 is operated manually to shift the clutch member 50 from the clutch member 49 into engagement with the clutch member 20. The belt 38 is now on the idle pulley 43 and the belt 39 is on the active pulley 42. The motor being in operation, the shaft 46 will be rotated at reduced speed and the clutch 50 being 45 in engagement with the clutch 20 will rotate the shaft 19 in a direction and to an extent to raise the elevator. The cake or block of ice on the elevator is thereby raised between the scorers 36 so that vertical score lines are 50 formed on opposite sides of the ice cake or block. At the proper time a cam 88 (Figs. 1 and 2) on the upper end of the elevator engages a projection 89 from the rod 74 and shifts said rod toward the right (Fig. 5) to an 55 extent to shift the belts 38 and 39 respectively from the idler pulley 43 to the active pulley 44 and from the active pulley 42 to the idler pulley 40, thus reversing the direction of rotation of the shaft 46 and permitting the elevator and the weight of the ice thereon to re-

verse the direction of rotation of the shaft 19 at the same rate of speed at which the shaft 46 is rotated. This is because the clutch 50, which is keyed to the shaft 46, is still in engagement with the clutch 20, which is attached to the shaft 19.

When the elevator reaches its lowest position the weight of the elevator is no longer supported by the chains 17. The shaft 19 is then immediately stopped from further rotation by a lug 90 on one of the rolls 18 abutting against an arm 91 pivoted on an axis 92 at right angles to the axis of the shaft 19. The end of the arm 91 is in the groove of the roller 18 so that said arm is oscillated as the roller turns but constitutes a laterally rigid abutment to stop the shaft 19 from further rotation when the elevator reaches the bottom. The weight of the elevator being no longer supported by the shaft 19 the pressure against the sliding clutch member 50 is eased to such an extent that the spring 53 immediately shifts the rod 52 to an extent to move the clutch member 50 out of engagement with the clutch member 20. That is to say, at this time the spring 53 shifts the clutch member 50 into engagement with the clutch member 49 in order to operate the devices that eject the cake or block of ice from the machine.

Thus the clutch member 49 is rotated with the clutch member 50 with the result that the chain 61 rotates the shaft 63 and thereby the shaft 65 which operates the chain 68, causing one of the arms 69 to engage the rear of the cake or block of ice and move the same from the elevator onto a track comprising angle bars 93 (Fig. 3). During such movement the cake or block of ice is moved between the scorers 24 so that horizontal scores are formed in opposite sides of the ice. The ice is thereby moved below and beyond the sliding abutment 83. After the ice passes beyond said sliding abutment one of the projections 73 engages the arm 87 and thereby moves the clutch 84 from under the sliding abutment 83, permitting said abutment to drop to its lower position.

Since the rod 70 was restored to its initial position by the cam 88 in the manner above described one of the abutments 73 will again engage the arm 72 and the cycle of operation will be repeated.

The various rotary scoring devices are provided with shields 94 for safety.

From the foregoing it will be seen that my invention is automatic in most of its operations, the only manual manipulation being the shifting of the clutch member 50. The machine comprises a comparatively small number of parts and is highly efficient in that it saves a large amount of manual work and scores the ice cakes or blocks uniformly. I contemplate such variations as may be deemed expedient and without restricting myself in

any particulars I claim and desire to secure by Letters Patent:—

1. An ice scoring machine comprising an elevator arranged to raise and lower a cake or block of ice, an abutment at one end of said elevator, mechanism for raising and lowering said elevator, means for moving said abutment to an ineffective position when said elevator is raised, means for holding said abutment in said ineffective position, an ejector operable after said elevator is lowered for moving a cake or block of ice from said elevator and releasing said abutment holding means.
15. 2. An ice scoring machine comprising an elevator arranged to raise and lower a cake or block of ice, an abutment at one end of said elevator, mechanism for raising and lowering said elevator, means for moving said abutment to an ineffective position when said elevator is raised, means for holding said abutment in said ineffective position, mechanism for moving a cake or block of ice from said elevator after said elevator is lowered, and means for releasing said abutment by said last named mechanism.
20. 3. An ice scoring machine comprising an elevator arranged to receive and support a cake or block of ice, a movable abutment for stopping the ice in position on the elevator, mechanism for raising and lowering the elevator, devices for forming scores in opposite sides of the cake or block of ice when the elevator is raised as aforesaid, means for moving said abutment to position to permit the ice to be moved from the elevator, a latch for supporting the abutment in said position, an ejector for moving the ice from said elevator, and means operable by said ejector for releasing said latch.
25. 4. An ice scoring machine comprising an elevator arranged to receive and support a cake or block of ice, a movable abutment for stopping the ice in position on the elevator, mechanism for raising and lowering the elevator, devices for forming scores in opposite sides of the cake or block of ice when the elevator is raised as aforesaid, means for moving said abutment to position to permit the ice to be moved from the elevator, a latch for supporting the abutment in said position, and means for moving the ice from the elevator and releasing said latch.
30. 5. An ice scoring machine comprising an elevator arranged to receive and support a cake or block of ice, a movable abutment for stopping the ice in position on the elevator, mechanism for raising and lowering the elevator, devices for forming scores in opposite sides of the cake or block of ice when the elevator is raised as aforesaid, means for moving said abutment to position to permit the ice to be moved from the elevator, a latch for supporting the abutment in said position, a vertical shaft driven by said second shaft, and an ejector driven by said vertical shaft for moving the cake or block of ice from said elevator.

means operated by said ice moving means for releasing said latch, and automatic mechanism for controlling the operation of said ice moving means.

6. An ice scoring machine comprising an elevator arranged to receive and support a cake or block of ice, a movable abutment for stopping the ice in position on the elevator, mechanism for raising and lowering the elevator, devices for forming scores in opposite sides of the cake or block of ice when the elevator is raised as aforesaid, means for moving said abutment to position to permit the ice to be moved from the elevator, a latch for supporting the abutment in said position, means for moving the ice from the elevator, and means operated by said ice moving means for releasing said latch to permit said abutment to move to its initial position.

7. An ice scoring machine comprising an elevator arranged to raise and lower a cake or block of ice, a shaft, connections from said elevator to said shaft, mechanism for rotating said shaft in one direction to operate said connections and raise the elevator and to rotate said shaft in the opposite direction to permit the elevator to descend, an additional shaft which is parallel with said first shaft, connections for rotating said additional shaft by said first shaft, a clutch controlling operation of said connections by said first shaft, an ejector for moving the cake or block of ice from said elevator, an abutment normally arranged to stop the cake of ice in said elevator, means whereby raising and lowering said elevator renders said abutment ineffective to thus enable ejection of said cake of ice, means operable by said ejector to effect rearrangement of said abutment in effective position, and devices operated by said second shaft for operating said ejector.

8. An ice scoring machine comprising a rigid supporting frame open at its opposite ends to permit a cake or block of ice to enter said frame at one end and to pass from said frame at the opposite end, an elevator in said frame for receiving and supporting the cake or block of ice, a shaft mounted longitudinally in said frame, spaced connections from said elevator to said shaft, driving mechanism, a clutch rotated by said driving mechanism, means for rotating said clutch by said driving mechanism in one direction to rotate said shaft to operate said connections and thereby raise said elevator and for rotating said clutch in the opposite direction to permit said elevator to descend, an additional shaft parallel with said first shaft, connections operative by said clutch for rotating said additional shaft, means for moving said clutch to position to operate said connections, a vertical shaft driven by said second shaft, and an ejector driven by said vertical shaft for moving the cake or block of ice from said elevator.

9. A scoring machine comprising a rigid frame, a shaft journaled for rotation in opposite directions in said frame, scoring devices supported by said frame, an elevator operative by said shaft to support and move a cake or block of ice against said scoring device, a driving shaft for said first shaft, a cylindrical shaft mounted on and enclosing a part of said driving shaft, mechanism for rotating said cylindrical shaft selectively in opposite directions, mechanism for rotating said driving shaft in opposite directions by said cylindrical shaft, and a clutch for rotating said first shaft by said driving shaft. 70
10. A scoring machine comprising a rigid frame, a shaft journaled for rotation in opposite directions in said frame, scoring devices supported by said frame, an elevator operative by said shaft to support and move a cake or block of ice against said scoring device, a driving shaft for said first shaft, a cylindrical shaft mounted on and enclosing a part of said driving shaft, mechanism for rotating said cylindrical shaft selectively in opposite directions, mechanism for rotating said driving shaft in opposite directions by said cylindrical shaft, a clutch for rotating said first shaft by said driving shaft, an ejector for moving the cake or block of ice from said elevator, and means operated selectively by said clutch for operating said ejector. 15
11. An ice scoring machine comprising scoring mechanism, a support for supporting and moving a cake or block of ice into contact with said scoring mechanism, a shaft, a cylindrical shaft mounted on and enclosing a part of said first shaft, mechanism for rotating said cylindrical shaft, gearing for rotating said shaft by said cylindrical shaft, an ejector for moving the cake or block of ice from said support, driving connections for operating said ejector, and means for operating said connections by said first shaft. 20
12. An ice scoring machine comprising scoring mechanism, a support for supporting and moving a cake or block of ice into contact with said scoring mechanism, a shaft, a cylindrical shaft mounted on and enclosing a part of said first shaft, mechanism for rotating said cylindrical shaft, gearing for rotating said shaft by said cylindrical shaft, an ejector for moving the cake or block of ice from said support, driving connections for operating said ejector, a clutch device for operating said connections by said first shaft, and means driven by said clutch device for operating said support to move a cake or block of ice against said scoring devices. 25
13. An ice scoring machine comprising a support for supporting and moving a cake or block of ice, scoring devices for scoring the cake or block of ice automatically and as an incident to the movement of said cake or block by said support, two axially aligned shafts, a clutch device mounted on one of said
- shafts, a clutch member mounted on the other shaft, means for moving said clutch device into engagement with said clutch member to rotate said other shaft and for moving said clutch device out of engagement with said clutch member to permit said one shaft to rotate while said other shaft remains stationary, an ejector for moving the cake or block of ice from said support, and means operative by said clutch device for operating said ejector while said other shaft remains stationary. 30
14. An ice scoring machine comprising a support for a cake or block of ice, two axially aligned shafts, a clutch device mounted on one of said shafts, a clutch member mounted on the other shaft for engagement by said clutch device to rotate said other shaft, connections operated by said other shaft for raising and lowering said support, an ejector for moving the cake or block of ice from said support, a clutch element mounted on said one shaft for engagement and rotation by said clutch device, and means for moving said clutch device into engagement with said clutch element to thereby operate said ejector while said other shaft remains stationary. 35
15. An ice scoring machine comprising a support for a cake or block of ice, two axially aligned shafts, a clutch device mounted on one of said shafts, a clutch member mounted on the other shaft for engagement by said clutch device to rotate said other shaft, connections operated by said other shaft for raising and lowering said support, an ejector for moving the cake or block of ice from said support, a clutch element mounted on said one shaft for engagement and rotation by said clutch device, means for moving said clutch device into engagement with said clutch element to thereby operate said ejector while said other shaft remains stationary. 40
16. An ice scoring machine comprising a support for a cake or block of ice, two axially aligned shafts, a clutch device mounted on one of said shafts, a clutch member mounted on the other shaft for engagement by said clutch device to rotate said other shaft, connections operated by said other shaft for raising and lowering said support, an ejector for moving the cake or block of ice from said support, a clutch element mounted on said one shaft for engagement and rotation by said clutch device, means for moving said clutch device into engagement with said clutch element to thereby operate said ejector while said other shaft remains stationary, and mechanism for rotating said one shaft in one direction when said clutch device is in engagement with said clutch member and in the opposite direction when said clutch device is in engagement with said clutch element. 45
17. An ice scoring machine comprising a

5   rotary shaft, a support for a cake or block of ice, flexible connections from said support to said shaft whereby rotation of said shaft in one direction will raise said support and rotation of said shaft in the opposite direction will permit said support to descend, a driving shaft in axial alinement with said rotary shaft, an ejector for moving the cake or block of ice from said support, driving connections for operating said ejector, and a device 10 mounted on said driving shaft for rotating said first shaft or operating said driving connections as desired.

15   18. An ice scoring machine comprising a driving shaft, a cylindrical shaft in which said driving shaft is mounted, mechanism for rotating said cylindrical shaft in either direction, means for driving said driving shaft by said cylindrical shaft, a shaft in axial alinement with said driving shaft, a device 20 for rotating said last named shaft by said driving shaft, means for moving said device to position to permit said driving shaft to rotate while said last named shaft remains 25 stationary, scoring devices, and a support operated by said last named shaft for moving a cake or block of ice into engagement with said scoring devices.

30   19. An ice scoring machine comprising a driving shaft, a cylindrical shaft in which said driving shaft is mounted, mechanism for rotating said cylindrical shaft in either direction, means for driving said driving shaft by said cylindrical shaft, a shaft in axial alinement with said driving shaft, a device 35 for rotating said last named shaft by said driving shaft, means for moving said device to position to permit said driving shaft to rotate while said last named shaft remains stationary, scoring devices, a support operated by said last named shaft for moving a cake or block of ice into engagement with said scoring devices, an ejector for moving the cake or block of ice from said support, and mechanism controlled by said device for operating said ejector while said last named shaft remains stationary.

40   20. An ice scoring machine comprising a driving shaft, a cylindrical shaft enclosing a part of said driving shaft, gearing for rotating said driving shaft by said cylindrical shaft, mechanism for rotating said cylindrical shaft and thereby said driving shaft alternately in opposite directions, scoring devices, a support for a cake or block of ice, and mechanism operated by said driving shaft for raising and for controlling the descent of said support to move the cake or block of ice thereon into contact with said scoring devices.

45   21. An ice scoring machine comprising a driving shaft, an operating shaft co-axial with said driving shaft, gearing for rotating said driving shaft by said operating shaft, mechanism for rotating said operating shaft

and thereby said driving shaft alternately in opposite directions, scoring mechanism, means for operating said scoring mechanism, and mechanism operated by said driving shaft for moving a cake or block of ice into contact with said scoring mechanism.

50   22. An ice scoring machine comprising a driving shaft, an operating shaft co-axial with said driving shaft, gearing for rotating said driving shaft by said operating shaft, mechanism for rotating said operating shaft and thereby said driving shaft alternately in opposite directions, scoring mechanism, means for operating said scoring mechanism, mechanism operated by said driving shaft for moving a cake or block of ice into contact with said scoring mechanism, an ejector for moving a cake or block of ice from the machine, and mechanism operated by said driving shaft for operating said ejector.

55   23. An ice scoring machine comprising a rigid frame having open ends to receive and discharge cakes or blocks of ice, an elevator mounted in said frame for receiving and supporting the cakes or blocks of ice successively and having open ends to permit the cakes or blocks of ice to move onto the elevator at one end and to move from the elevator at the other end, scoring devices supported by said frame at the sides of said elevator, a rotary shaft supported by said frame parallel with the line of movement of the cakes or blocks of ice through said frame, spaced flexible connections from said elevator to said shaft for raising and lowering said elevator by said shaft, a clutch device, means for shifting said clutch device to and from position to rotate said shaft, a vertical shaft, mechanism controlled by said clutch device to rotate said vertical shaft when said clutch device is out of position to rotate said first shaft, and an ejector operated by said vertical shaft for moving the cakes or blocks of ice from said elevator.

60   24. An ice scoring machine comprising a rigid frame having open ends to receive and discharge cakes or blocks of ice, an elevator mounted in said frame for receiving and supporting the cakes or blocks of ice successively and having open ends to permit the cakes or blocks of ice to move onto the elevator at one end and to move from the elevator at the other end, scoring devices supported by said frame at the sides of said elevator, a rotary shaft supported by said frame parallel with the line of movement of the cakes or blocks of ice through said frame, spaced flexible connections from said elevator to said shaft for raising and lowering said elevator by said shaft, a clutch device, means for shifting said clutch device to and from position to rotate said shaft, a vertical shaft, mechanism controlled by said clutch device to rotate said vertical shaft when said clutch device is out of position to rotate said first shaft, an ejector

operated by said vertical shaft for moving the cakes or blocks of ice from said elevator, and scoring devices for scoring the cakes or blocks of ice during its movement by said ejector from said elevator.

25. In an ice scoring machine having ice moving means comprising an elevator and an ejector, means for alternately operating said elevator and said ejector comprising a shaft 46, a double-clutch element 50 mounted on and driven thereby, a clutch member 49 journaled on said shaft to be driven by said clutch element in one position thereof, a bearing 48 mounted at the extremity of said shaft 46, 10 a second shaft 19 having a clutch member 20 at its adjacent extremity and having said adjacent extremity mounted on said bearing 48 to position said clutch member 20 to be driven by said clutch element in a second position 15 thereof, means for driving said shaft 46 to drive said clutch element, and means connecting said clutch members individually for driving said elevator and ejector.

26. In an ice scoring machine having an elevator and ejector and a reversible drive adapted to drive in one direction and couplable for raising said elevator and adapted to drive in the other direction for lowering said elevator and thereafter operating said 25 ejector, drive reversing means embodying snap action means for maintaining said drive in either direction until positively reversed, drive control means comprising means for coupling said drive while operating in the 30 first mentioned direction for raising said elevator, means carried by said elevator for shifting said drive-reversing means when said elevator reaches the top of its movement to effect lowering of said elevator and for 35 simultaneously positioning a lever in operable relation to said ejector, automatic means for shifting said drive from said elevator to said ejector without reversal thereof when said elevator reaches the bottom of its travel, and 40 means carried by said ejector for moving said lever after ejection of the block from the machine to positively shift said drive reversing means and disconnect said drive from said elevator and ejector.

45. 27. In an ice scoring machine having an ice passage therethrough and an elevator in said passage for receiving a block of ice and reciprocating it transversely; abutment means for stopping the ice in position to be reciprocated by said elevator; means operable upon reciprocation of said elevator for moving said abutment means to, and retaining it in, ineffective position; an ejector for moving the ice from said elevator and out of the machine; 50 and means operable by said ejector for re-positioning said abutment to stop the next block of ice entering the elevator.

55. 28. In an ice scoring machine having an ice passage therethrough an elevator normally aligned in said passage for receiving a block

of ice passed therewith; abutment means normally arranged for stopping said block of ice in said elevator; driving means for raising and lowering said elevator; means operable upon reciprocation of said elevator for moving said abutment to, and retaining it in, ineffective position; ejector means for moving said ice block from the elevator; automatic means for disconnecting the driving means from said elevator and connecting operating means for said ejector means upon return of said elevator to alignment with said passage; means controlled by said ejector means for effecting return of said abutment to normal position as said cake of ice is being ejected; and means operated by said ejector means for disconnecting the operating means from said ejector means after said cake of ice has been ejected.
